DESIGN FOR A BOOK END

Arthur S. Leitner, Los Angeles, Calif.

Application October 28, 1948, Serial No. 134,351

Term of patent 14 years

(Cl. D33—1)

To all whom it may concern:

Be it known that I, Arthur S. Leitner, a citizen of the United States, residing at Los Angeles, in the county of Los Angeles and State of California, have invented a new, original, and ornamental Design for a Book End, of which the following is a specification, reference being had to the accompanying drawing forming part thereof.

Fig. 1 is a front perspective view of a book end showing my new design.

Fig. 2 is a rear perspective view thereof.

I claim:

The ornamental design for a book end, substantially as shown.

ARTHUR S. LEITNER.
